UNITED STATES PATENT OFFICE

RICHARD P. MILBURN, OF NEWARK, NEW JERSEY, ASSIGNOR TO STANDARD OIL DEVELOPMENT COMPANY, A CORPORATION OF DELAWARE

TUBE AND BULB DEVICE

Application filed August 26, 1929. Serial No. 388,292.

This invention relates to improvements in tube and bulb devices, particularly for medicine droppers, nasal douches, sprayers or atomizers, and the like. A principal object 5 of the invention is to provide means for positively retaining the bulb in contact with the tube when the device is used with liquids which tend to cause swelling of the bulb material.

10 Reference is to be made to the accompanying drawing, in which

Fig. 1 is a vertical section through a preferred form of medicine dropper attached to a bottle;

15 Fig. 2 is a plan view of the retaining ring; and

Fig. 3 is a perspective view of the dropper.

In the drawing, 1 denotes a resilient bulb, preferably of rubber, having an annular flange 2. The bulb tapers at its base or lower end 3, in which there is a circular opening 4. This receives the end of a suction tube 5. The wall of opening 4 is recessed or threaded at 6 and the end of the tube 5 is correspondingly 20 formed with ridges 7 adapted to be fitted snugly in the opening 4. The flange 2 seats against the rigid screw cap 8, or other closure with which the bulb is to be used. The body of the bulb protrudes 25 through an opening in the cap or closure and frictionally engages the walls of the opening, whereby the bulb and the suction or dropper tube are supported.

I have found that the swelling and resulting looseness of rubber suction bulbs used with oily liquids may be avoided by placing a substantially non-resilient ring or band 9 inert to the liquid about the lower end of the bulb where it engages the tube. The strength 30 and rigidity of the ring must be sufficient to withstand any expansion force due to distortion of the bulb material.

The ring 9 has preferably an inside diameter 45 a trifle less than the outside diameter of the lower end of the bulb. It is sufficient if the ring will keep its position by frictional engagement with a new bulb.

When placed as shown, the ring binds or 50 presses the bulb against the tube and any

swelling of the bulb material only makes the engagement tighter.

Celluloid, steel or the like are suitable materials for the ring. It is simpler and entirely satisfactory for most purposes to make 55 the ring in one piece. I may however use split rings or any equivalent device for securing good contact between the parts. It is understood, however, that I do not claim the use of a clamping ring for holding in place 60 a rubber article not subject to distortion by the liquid with which it comes in contact. The present invention is based on the conception of providing a means for receiving the outward thrust of swelling material and caus- 65 ing this normally destructive force to provide a satisfactory and lasting engagement between tube and bulb.

The foregoing description is illustrative only and various alternative arrangements 70 and uses are included within the scope of the appended claims, in which it is my intention to claim all novelty inherent in the invention.

I claim:

1. A combined bottle closure and liquid 75 dropper comprising a cap having an opening and adapted to fit over and form a cover for the top of a bottle, and a liquid dropper including a tube, a bulb provided with a base engaging a portion of the tube, a ring impressing a portion of the base against the tube, and a flange projecting from the bulb radially beyond the ring in spaced relation to the base, the dropper bulb extending through the opening with the flange seating against the cap. 85

2. A combined bottle closure and liquid dropper comprising a cap having an opening in it and adapted to fit over and form a cover for the top of a bottle, and a liquid dropper comprising a flanged elastic bulb having a 90 dropper tube engaged in the bottom of the bulb, said bulb being extended upwardly through the opening in said cap with the dropper tube projecting therebelow and the flange over the greater part of its area seated 95 against the under side of the cap.

3. A combined bottle closure and liquid dropper comprising a rigid cap having a central opening in it and adapted to fit over and 100 form a cover for the top of a bottle and a

- liquid dropper consisting of an elastic bulb having a dropper tube engaged in an open neck forming the bottom of the bulb, said bulb being extended upwardly through the opening in said cap with the dropper tube projecting therebelow and the body of the bulb frictionally engaging the cap whereby the bulb and dropper tube are solely supported when the cap and bulb are removed from the bottle.
- 10 4. A combined liquid dropper and closure for the neck of a bottle, comprising a cap having a top with an opening in it, said top being adapted to fit over and extend inwardly from the bottle neck to form a cover for the bottle, and a liquid dropper comprising an elastic bulb having a single top-engaging flange, a dropper tube engaged in the bottom of the bulb, said bulb being extended upwardly through the opening in the top of said cap with the dropper tube projecting therebelow, and the flange over the greater part of its area seated against the under side of the top of the cap.
- 15 20 25
